UNITED STATES PATENT OFFICE.

WALTER LUTTRINGHAUS, OF MAYWOOD, ILLINOIS.

DESIGN FOR A PERCOLATOR.

48,559.

Specification for Design.

Patented Feb. 15, 1916.

Application filed March 27, 1915. Serial No. 17,549. Term of patent 7 years.

To all whom it may concern:

Be it known that I, WALTER LUTTRINGHAUS, a citizen of the United States, residing at Maywood, in the county of Cook and State of Illinois, have invented a new, original, and ornamental Design for Percolators, of which the following is a specification, reference being had to the accompanying drawing, forming a part thereof.

The figure is a perspective view of a percolator showing my new design.

I claim:

The ornamental design for a percolator, as shown.

WALTER LUTTRINGHAUS.

Witnesses:

OLAF TOLLAGSEN,
JOHN A. DIENNER.
